UNITED STATES PATENT OFFICE.

WILFRED R. TOBIAS, OF LOS ANGELES, CALIFORNIA.

ROOF.

Application filed August 10, 1927. Serial No. 211,911.

My invention is a roof of the slate, shingle or tile type.

An object of my invention is the construction of a roof formed of slate, shingles or flat tiles, in which the slates are laid in such a manner as to give an improved architectural effect, especially by giving deeper shadows with comparatively thin slates than with the same slates laid in the ordinary manner. 10 Moreover, the manner of laying the slates allows giving a variation to the structure and adding to the ornamental characteristics of the roof.

Another object of my invention from a structural standpoint is the laying of the slates in an overlapping manner, running from one end of the roof to the other, successive roofs overlapping in opposite directions so that the slates are securely bound to the 20 roof, the overlapping rows binding the lower rows and the layers being double and triple thick in some places.

In one form of constructing my invention I lay a row of slates adjacent the eaves, this 25 row starting at one end and each layer overlapping the side edge of the adjacent slate. The second row starts from the opposite end of the roof and the slates overlap in the opposite direction, the third row being a repetition of the first row adjacent the eaves. As 30 a variation of this construction the individual slates of each row are made of different lengths so as to have a staggered effect at their lower edge. In a still further modification of the roof structure the slates are constructed of large and preferably substantially uniform size and have smaller cover strips secured thereon and positioned centrally of each individual slate.

40 My invention in several of its aspects is illustrated in the accompanying drawings, in which:

Figure 1 is a perspective view of a simple form of my roof construction.

45 Figure 2 is a plan view of a modification, showing the slates staggered.

Figure 3 is a vertical section of Fig. 2 on the line 3—3 in the direction of the arrows.

Figure 4 is a plan view of a further modification showing the overlaid ornamental slates.

Figure 5 is a section of Fig. 4 on the line 5—5 in the direction of the arrows.

55 Figure 6 is a perspective view of another form of my roof in which the rows of slates overlap from one side.

In the construction of Fig. 1 the supporting structure of the roof is designated by the numeral 11. This may be of any character and made of any suitable material. The 60 first row 12 of the slates is illustrated as starting at the right hand end, in which the slate 13 is the first slate laid, and the next slate 14 overlaps this, as indicated at 15, the side edge 16 of the upper slate extending towards the ridge of the roof and at right angles to the eaves of the roof. All of the 65 slates of this first row are laid in the same manner, that is, they may be considered as overlapping the slate to the right. These 70 slates are secured to the roof structure by nails or similar fastenings through the upper edge of each slate as is the common practice.

The second row 17 starts with a first slate 18 at the left hand side of the roof and the next slate 19 thereto overlaps to the left, with its side edge 20 being at right angles to the eaves of the roof and leading towards the ridge. All of the slates of this row are laid 75 in the same manner, overlapping each other 80 to the left. In this type of roof it is not necessary that the slates of the different rows break joint, as there is no objection to the exposed edges 21 of an under row being substantially in alignment with the covered edge 85 22 of the row next above, etc.

The third row of slates 23 is laid in the same manner as the first row, starting from the right hand side of the roof and working towards the left hand side, the slates in this 90 row overlapping each other to the right. It is to be understood that each row of slates has an overlap over a lower row, as is the ordinary practice in laying slates, sufficient to prevent any back running of water in passing off the roof from working up underneath 95 the slates.

A characteristic feature of this form of construction is that part of the exposed edges of the slates, looking from the eaves towards the ridge of the roof, shows slates of one thickness, as indicated at 24, while, where the slates overlap as at 25, they show a double thickness of slates. Manifestly at these double thick portions there are actually three 105 thicknesses of slate, measured upwardly from the roof, and at the parts indicated at 24, there are two thicknesses of slate.

In the modification of Fig. 2 the lower row of slates 30 is indicated as being started from 110 the left hand end 31. The next slate 32 there-to overlaps to the left, as indicated at 33, and

a third slate 34 overlaps the second slate to the left. These slates, however, have their lower edges 35 and 36 offset or stepped up, that is, each alternate slate has its lower edge 5 higher up the roof than the adjacent slate on each side. In this construction it gives a desirable effect to have the edges, indicated at 35, in substantial alignment with the eaves of the roof, or possibly partly projecting 10 slightly outside of the eaves of the roof and the edges 36 extending beyond the eaves of the roof. This arrangement is effected by using slates of different length, as indicated at 37 and 38, for although the slates have an offset as indicated at 39 at their upper edge where they are secured to the roof by nails 40 or other fastenings, yet the lower edges have a very much greater offset or stagger 15 than the upper edges.

20 A second row of slates, designated by the numeral 41, is started with a first slate 42 on the right hand side of the roof, the next slate 43 overlapping, as indicated at 44. Such row is continued from one side of the roof to the 25 other, building up the roof in somewhat the same manner as in Fig. 1. With this arrangement of slates and also using some slates longer than others, there is no distinct row 30 of slates showing as viewed from the ground or the level of the roof, but the edges of the slates appear in a staggered relation, that is, adjacent slates having their lower edges either towards the eaves or towards the ridge 35 of the roof. The roof built up in this manner also has sections with a single and a double thickness of slate showing from the edge, thus giving a variation in the appearance and in the shadows formed by the slates.

40 In the construction of a roof as illustrated in Figs. 4 and 5, the lower row 50 of slates is indicated as having the lower edges 51 in alignment, the first slate of the row indicated at 52 being started on the left hand side of the roof and the succeeding slates overlapping 45 at the left, as indicated at 53. Before laying the second row, there are laid a series of ornamental pieces 54 which are positioned substantially in the middle of the exposed part of each slate and have their lower edges 55 at any suitable distance between the lower edges of each of the rows of slates.

50 The second row of slates 56 also has its lower edge parallel to the lower edge of the first row, and the first slate of this row, indicated at 57, starts on the right hand side of the roof, and the next slate 58 overlaps to the right, as indicated at 59. This type of roof has the same characteristics in laying the main slates as set forth in connection with 55 the laying of the slates in Figs. 1, 2, and 3, and has in addition, the ornamental strips 54. The ornamental strips are secured by nails 60 which are driven into the roof structure 65 slightly above the nails 61 which hold the main slates of each row. This arrangement

gives a slight open space on each side of the ornamental pieces as indicated at 62, allowing a certain circulation of air underneath the slates, adding materially to the coolness of the roof when used in hot climates. 70

It is obvious that many other changes may be made in the design of roofs, using the principles above mentioned of overlapping the different rows of slates when working in different directions, considered from the sides 75 of the roof, and that various ornamental shapes and colors of slates and cover pieces may be utilized.

Fig. 6 indicates a further modification of my invention in which the lowest row 70 of 80 slates is indicated as being built from the right hand side 71 of the roof, and each succeeding slate overlaps a lower to the right, as indicated at 72. The next row 73 considered upwardly of the roof is also built up in 85 the same manner, with the slates overlapping to the right, the same as the lower row. The third row 74 is also built up in the same manner.

90 It is to be understood, of course, that the slates may be built so as to overlap to the left. This type of roof, however, involves the feature of the slates of each succeeding row, all overlapping in the same direction as in the adjacent rows. In all the constructions it 95 is also to be understood that the slates may be arranged to have an overlap, that is, to break joint much in the same manner as in the ordinary slate roof.

95 Various changes may be made in the principles of my invention without departing from the spirit thereof, as set forth in the description, drawings and claims. 100

I claim:

1. A roof having a roof structure with rows 105 of slates thereon, one row having the slates arranged in an overlapping relation considered from one side of the roof to the other, and an adjacent row having the slates overlapping from the other side of the roof. 110

2. A roof having an under structure with rows of slates thereon, one row of slates being arranged with each slate overlapping the next slate to the right, and an adjacent row having each slate overlapping the next slate to 115 the left.

3. A roof having an under structure with slates thereon, the slates of each adjacent row being arranged to overlap in opposite directions and the lower edges of the slates in each 120 row showing portions one slate thick between the overlap and two slates thick at the overlap.

4. A roof having an under structure with rows of slates thereon, upper rows of slates overlapping a lower row considered from the 125 eaves towards the ridge of the roof and each row having slates overlapping at their side edges, the adjacent rows overlapping from opposite directions.

5. A roof having an under structure with 130

slates thereon, the slates being arranged substantially in rows considered from the eaves towards the ridge of the roof, the slates of one row overlapping in one direction and the 5 slates of an adjacent row overlapping in the opposite direction considered from the sides of the roof, and the lower edges of the alternate slates of each row being staggered whereby every alternate slate has its lower edge at 10 a different distance from the eaves from the alternate slates therebetween.

6. A roof having an under structure with slates thereon, the slates being arranged substantially in rows considered from the eaves 15 towards the ridge of the roof, the slates of one row overlapping in one direction and the slates of an adjacent row overlapping in the opposite direction considered from the sides

of the roof, and the lower edges of the alternate slates of each row being staggered whereby every alternate slate has its lower edge at a different distance from the eaves from the alternate slates therebetween, and the adjacent slates of each row being of different lengths with their upper edges approximating a line along the roof. 20 25

7. A roof having a roof structure with rows of slates thereon, some rows having the slates overlapping considered from one side to the other, and other rows having the slates overlapping considered from the other side of the roof. 30

In testimony whereof I have signed my name to this specification.

W. R. TOBIAS.
